UNITED STATES PATENT OFFICE.

WILLIAM A. SHEAHAN, OF FREEPORT, ILLINOIS, ASSIGNOR TO SHEAHAN ROTARY ENGINE COMPANY, OF CHICAGO, ILLINOIS, A CORPORATION OF NEW JERSEY.

ROTARY ENGINE.

No. 806,297.

Specification of Letters Patent.

Patented Dec. 5, 1905.

Application filed May 13, 1902. Serial No. 107,111.

To all whom it may concern:

Be it known that I, WILLIAM A. SHEAHAN, a citizen of the United States of America, residing at Freeport, county of Stephenson, and 5 State of Illinois, have invented certain new and useful Improvements in Rotary Engines, of which the following, taken in connection with the accompanying drawings, is a specification.

This invention has reference to the provision 10 of an improved form of Rotary Engine employing a parti-spherical cylinder, in combination with a piston therein of substantially the shape of a spherical sector, and has for its primary object the construction of a motor 15 device of this character in which the spherical sector or piston will have its axis common with the axis of rotation of the shaft of the engine, and in which the engine shaft and piston will be preferably integral, with the steam 20 inlet arranged to pass through the shaft and piston, and in which the radial axis of the parti-spherical cylinder will be oblique to the axis of the shaft, so that the employment of a piston blade mounted in the piston in a slot 25 formed therein, so as to permit of a rocking or oscillating motion of the blade, will provide means for imparting movement to the piston and shaft.

By the combination of the instrumentalities 30 above referred to, I am enabled to provide a Rotary Engine which is capable of attaining very high speed of rotation with a very low cost for steam, and which will at one and the same time be very cheap and easy to construct, 35 and simple and easy to repair, and which will not be liable to get out of order on account of the simplicity of the mechanism, and the operation of the piston and shaft about a common axis of rotation.

40 A further object of my invention is the provision for use of an improved form of self-operating valve for a motor, in which I employ in combination two triangular shaped ports, one in the shaft or valve seat, and one in 45 the sleeve surrounding the shaft or seat, said triangular ports being so disposed relative to each other as that longitudinal movement of the sleeve relative to the shaft or seat will determine with accuracy and reliability the extent 50 of opening of the valve ports, so that the steam may be admitted either during nearly the whole of the rotation of the device, or for any predetermined part thereof, as may be desired.

The above, as well as such other objects as 55 may hereinafter appear, I attain by means of a construction which I have illustrated in the accompanying drawings, in which

Figure 1 is a side elevation showing an engine embodying my improvements, 60

Figure 2 is a view with the cylinder-head removed, showing the interior of the cylinder and the piston, and piston blade in elevation,

Figure 3 is a transverse sectional view on the line 3 of Figure 1, 65

Figure 4 is a perspective view of the piston blade which I employ,

Figure 5 is a longitudinal sectional view on a vertical plane, and

Figure 6 is a detail showing certain parts 70 of the valve mechanism.

Referring first to Figure 1, it will be seen that on a base 7 I mount a couple of uprights or standards 8 and 9, the standard 8 being arranged to carry the parti-spherical cylinder 75 10, which has its head arranged preferably in a plane which is at an angle with reference to the base, and so that the head will be oblique to the axis of rotation of the engine shaft 11, which is shown as carrying a couple 80 of pulleys 12 and 13, and mounted to rotate within the stuffing boxes 14, 15, 16, and 17.

Within the cylinder 10 the shaft 11 is provided with a rotary piston 18, which is preferably integral with the shaft, and constitutes in 85 effect an enlargement of the shaft of the shape shown, carrying within it a groove or channel 19, within which is mounted a piston blade 20, which is adapted to oscillate about the pin 21 within the groove 19, as the rotation of the shaft 90 causes the blade to be rotated with the piston, and the right hand edge of the blade is in contact with either the inner face of the cylinder-head 22 or with the bearing plate 23 of the inner face of the cylinder-head, which inner face 95 stands in a plane at an oblique angle to the axial line of the shaft, as shown.

The piston blade 20 is provided with a kind of semi-circular projection 24 engaging with the blocks or spring held packing devices 25, 100 to prevent the steam from leaking out to the right, and there is also provided on the blade 20 a bearing edge 26, which is adapted to be pressed or held outwardly into contact with the interior of the cylinder wall by means of 105 the centrifugal force, so as to not only make a tight joint between the blade and the interior of the cylinder, but also at the same time

to allow for more or less expansion and contraction between the several parts.

- In order to make a tight joint between the inner face of the cylinder-head and the adjacent edge of the piston blade, I provide a half round bearing strip 28, disposed as shown, and provided at its back with a packing strip 29, which is held outwardly or in contact with the bearing strip by means of springs 30.
- 10 The piston 18 is provided with packing 31, as shown in Figure 3, for the purpose of making a tight joint between the piston and the interior of the cylinder. The right hand face 32 of the spherical sector which comprises the piston is made of such an angle as to just meet along the radius 33 of the plane of the inner face of the cylinder-head, so that in bearing against the bearing plate 23, it will make a steam tight joint, therewith, and in order to 15 more certainly insure a good fit at this point adjusting screws 34, with locknuts 35, are provided in the cylinder-head.

From the above, taken in connection with the drawings, it will be evident that the disposal of the parts referred to creates within the partispherical cylinder a steam space or chamber 36, which, from the bearing line along the radius marked 33, where the piston and cylinder-head are tangential and in contact, gradually widens, following around the shaft, until it reaches its widest point at the bottom, and then gradually narrows until it reaches the zero point again along the line 33. The inlet port 38 is therefore arranged just at 25 one side of the piston blade, the steam reaching such inlet port through the passage 39, and central opening 40, or passage in the shaft, so that the steam in following the piston blade around has a constantly increasing or expanding chamber within which to act upon the piston blade, and a constantly increasing area of the blade upon which to operate until the half blade in front of the steam inlet port reaches the lower half of its rotative movement, from 30 whence the chamber then begins to reduce until it comes around to the top. The exhaust 45 may be located in the cylinder head in any position relative to the rotation of the blade, which may be preferred, it being only necessary that it shall be at such a distance from the inlet port, and in such position as that it will not be possible for the inlet port and the exhaust port both to be open to the steam chamber at the same time. In Figure 2 I have 50 indicated in dotted lines the relative location of the inlet and exhaust port, although strictly speaking, since the cylinder-head is removed in this Figure, the exhaust port would not show in this view.

60 In the construction shown the inlet port follows around immediately behind one half of the piston blade, because the inlet port is situated in the piston head, and thus the steam acts only upon that half of the piston blade, and the other half should be perforated or

made in a kind of skeleton form, a number of such perforations being indicated in the lower half of the piston blade in Figure 4. If it be desired to make a double acting engine, or one which will not get upon a dead center, all 70 that is necessary is to place two of my piston devices on one shaft, setting the blades at an angle to each other, so that while one is exposing its maximum area to the steam pressure, the other one will be at some other part 75 of the rotative movement.

The inlet to the central passage 40 in the shaft is through a triangular port 41, with which registers another triangular port 42 in a valve-sleeve 43, which surrounds the shaft 80 as shown within a valve-chamber 44, at each side of which are stuffing boxes 14 and 15, the valve-chamber 44 being formed in the casing at the top of the standard 9. The sleeve 43 is arranged to be moved longitudinally relative 85 to the shaft by means of a rack 45 and pinion 46, the latter being mounted upon a shaft 47, upon the upper end of which is a handle 48 for manipulating the valve.

From an examination of Figure 5 it will be 90 seen that in the position of the valve parts therein shown no steam can enter the engine, but that as the sleeve 43 is moved to the left the port 41 will register, through a portion of its rotative movement, with the port 42, and 95 some steam will be admitted to the engine, whereas the further movement of the valve-sleeve 43 will still further open the port, increasing the length of time or portion of the rotation of the shaft, during which the steam 100 is admitted. The triangular ports are preferably arranged so that each is equal in length to a half the circumference of the shaft, so that all grades of regulation can be secured from zero to admission for practically the full 105 rotative movement of the shaft, since when the parallel sides of the ports 41 and 42 are near each other, it is obvious steam will continue to be admitted during near the entire 110 revolution of the shaft.

From the above it is obvious that I have so constructed the parts in my improved engine as that they shall act by such amount of cut-off as may be desired, from any point above zero to full stroke, or full revolution. Thus 115 I have produced a simple Rotary Engine, which works the steam expansively, since after the inlet port is cut off, as described, the steam in the piston chamber behind the piston blade continues to act upon the piston blade around 120 to the point where it reaches the exhaust port and escapes.

The operation of my invention is as follows:

Assuming that steam be admitted through the passages 40 and 39, it will enter the steam chamber and act against the piston blade, and 125 create a rotative movement thereof around the axis of rotation of the shaft, continuing to act upon the blade until it escapes through the exhaust pipe 40 by the blade passing the ex- 130

haust opening. As the piston rotates, the blade will not only rotate with it, but will of course be caused to oscillate about the pin 21 by the bearing of the right hand edge of the 5 blade upon the inner surface of the cylinder-head 22, which inner surface the right hand edge of the blade follows throughout the rotation of the same.

From the above it is evident that my device 10 embodies a construction in which the entire operation is practically about a common center, since the blade oscillates about a central point which is at the same time the center of rotation of the shaft and piston head, and also 15 the center of movement of the packing device in the edge of the piston blade. By this means 20 all tendency to vibratory motion or frictional loss is reduced to a minimum, the only relative movement which is not rotative being the oscillating movement of the piston blade relative to the piston head, and this I find to be 25 of such a character as does not produce material vibration or frictional loss. The piston blade it will be observed follows around 30 with its edge constantly in contact with the inner side of the cylinder head, passing over the packing plate 23, as already described, which is arranged to stand flush with the inner side of the cylinder-head, and can be set 35 inwardly by means of the adjusting devices shown, as it may wear a little because of the contact with it, not only of the edge of the piston blade as it passes over it, but also of the right hand surface of the spherical sector, 40 which is constantly touching along this radial line.

A ball bearing is provided at 50 to take the 45 end thrust on the shaft, the balls being arranged in a ball race, which is constructed so 50 that the whole can be taken out together without the balls falling out of place, this being accomplished by the hooks 51, shown in Figure 5.

By this construction I have not only provided 45 an engine in which the inlet port is carried around to follow the blade in the motion of the piston, and all leakage along the piston shaft and behind the piston itself is obviated by reason of the peculiar shape of the 50 slot 19, but I have provided an intermittent inlet valve which is self-operating and therefore allows of the engine working expansively 55 under the pressure of the steam through a part of its stroke. Also the location of the exhaust or outlet port in the head of the cylinder obviates the possibility of a dead center 60 in the engine and allows for easy provision for a double action engine as described. The taking up of the backward thrust of the vane 65 or piston blade by means of the pivot point 12 rather than by its resting upon the bottom of the slot 19 in the piston, is also of a great advantage as it obviates much of the friction of the engine. The compound motion of rotation 70 combined with that of simultaneous

oscillation of the piston-blade generally causes in such instance an angular rocking of the edge of the blade upon the piston head and I have obviated the effect of imperfect contact with the cylinder head from this cause by the 75 provision of the rocking bearing bead 28 set in the face edge of the piston blade as above described.

Where I have hereinabove referred to a partispherical cylinder, I desire it to be understood that I mean a cylinder which is only a part of a sphere, since it is obvious that it is not essential that an entirely spherical or entirely hemispherical cylinder should be used. The piston sector for example at the 80 back end could be cut off nearer to the right hand surface, and still the device would operate so long as the groove or slot within which the oscillating blade is housed was of sufficient width to cover the blade at all points 85 of its oscillation.

It is obvious that this machine, by reversal, could be used as a pump or compressor as well as an engine.

Having thus described my invention, what 90 I claim as new, and desire to secure by Letters Patent, is—

1. An engine comprising a rotary slotted piston, an oscillating piston blade operating in said slot in the piston, a cylinder having an 95 inclined head in contact with one radial line of said piston and with the edge of the piston blade, and means for introducing the pressure fluid through a traveling port in the piston behind said blade, substantially as described.

2. In a rotary engine a piston provided with a rotating retractile blade, a cylinder with an inclined head to coöperate with said blade, and a movable port for introduction of the 105 actuating fluid, substantially as described.

3. A rotary engine comprising the combination with a partispherical cylinder, of a shaft carrying a spherical sector piston, the radial axis of the spherical sector being common with 110 the axis of the shaft of the engine, the steam inlet being through the shaft and spherical sector, substantially as described.

4. A rotary engine comprising the combination with a partispherical cylinder, of a 115 spherical sector piston, the radial axis of the spherical sector being common with the axis of the shaft of the engine, and a steam inlet port in the piston traveling around with the piston, substantially as described.

5. A rotary engine comprising the combination of a partispherical cylinder, a shaft, a spherical sector piston, an oscillating blade, said piston and blade having a common center of motion, and an inlet port carried by said 125 piston in the rear of said blade, substantially as described.

6. An engine comprising a partispherical cylinder having an inclined head, a rotating piston in said cylinder cone-shaped to make 130

tangential contact with the head of the cylinder on one line, a retractile blade slotted in the piston, and a movable port for introducing the actuating fluid behind the blade.

5 7. A rotary engine having a rotary piston, a partispherical cylinder with an inclined head, and provision for introducing the motive fluid through the axis of the revolving piston, the outlet of the said port being movable with respect to the contact point between the cylinder head and the piston.

8. A rotary engine comprising a partispherical cylinder, a cone-shaped revolving piston, an inclined head to the cylinder in contact with 15 said conical piston on one line, a retractile piston blade slotted in the piston, said piston having an inlet port for the motive fluid movable with respect to the contact line between the cylinder head and the revolving piston.

20 9. In a rotary engine the combination with a partispherical cylinder, a rotary shaft and piston, and inclined head to the cylinder having an exhaust port, a conical face to the piston in contact on one line with the cylinder head, and a traveling port for the entrance of 25 the motive fluid provided in the face of said piston.

10. In a rotary engine a partispherical cylinder having a plane head provided with an exhaust port, a rotating cylinder and shaft with axis at an angle to the cylinder head, said piston having a conical face in contact with the cylinder head and being provided with an oscillating blade slotted in the piston, and means 30 for introducing motive fluid periodically between the blade and the tangential contact line between the cylinder head and the piston.

11. In a rotary engine the combination of a 40 casing having a flat face, a conical rotary piston with the cone in contact with said face, a pivoted and rotating retractile blade in said piston, a passage in the shaft of the piston and an inlet port for the motive fluid communicating periodically with the passage in the piston 45 and escaping behind said blade, substantially as described.

12. In a rotary engine the combination with a partispherical cylinder having a plane head, of a rotary conical piston in said cylinder having 50 its axis at an angle to the cylinder head, an oscillating piston blade slotted in the piston to coöperate with the cylinder head and an exhaust port in the cylinder head, and a traveling inlet port for the motive fluid 55 through the face of the rotating piston, substantially as described.

13. In a rotary engine the combination with a partispherical cylinder having a plane head, of a blade in said cylinder pivotally mounted 60 upon an axis rotating in a plane at an acute angle to the cylinder head.

14. In a rotary engine the combination of a cylinder, a driving shaft, a cylinder head set at an angle to the axis of the shaft, a rotating 65 piston on said shaft having a retractile blade

pivotaly mounted in a slot in the piston and rotating in a plane at an angle to the axis of rotation of the driving shaft.

15. The combination of a substantially hemispherical shaped cylinder, a driving shaft, a 70 piston on the shaft of substantially the same contour as the cylinder and provided with a substantially cone-shaped face of an obtuse angle, a transverse slot therein, a head secured to the cylinder at an angle to the axis of the shaft and in contact with an element of the conical piston and a blade mounted in the slot of the piston and in contact with the inner face of the cylinder head adapted to rotate parallel to the face of such cylinder head and 80 an inlet port through said piston behind the said blade, substantially as described.

16. In a rotary engine the combination of a cylinder having a plane head at an angle to the axis of rotation of the piston, a slotted 85 piston and a piston blade mounted upon a pivot and supported on said piston by means of a pin and rotating against the cylinder head and oscillating with respect to the axis of the cylinder and shaft, substantially as described. 90

17. In a rotary engine the combination with a partispherical cylinder having a plane head set at an angle to the axis of the piston, a piston in said cylinder rotating about a line at an angle to the cylinder head and having a retractile blade therein to coöperate with the cylinder head, an inlet port, an outlet port in the cylinder head, and means for intermittently admitting the motive fluid, substantially 95 as described. 100

18. In a rotary engine having a partispherical cylinder and a plane head and a rotating piston provided with an oscillating retractile piston blade, an adjustable bearing plate set in the cylinder head for coöperation with the contacting element of the conical piston, substantially as described. 105

19. In a rotary engine provided with a partispherical cylinder and a rotating and oscillating piston blade therein, a bearing plate for said piston blade slotted into the edge of the blade and having adjustable bearing edge for contact with the walls of the cylinder. 110

20. In a rotary engine having a rotary piston in a partispherical cylinder, a plane head 115 for said cylinder and a pivot for suspending the piston blade upon the end of the piston, substantially as described.

21. In a rotary engine the combination with a flat faced casing and a rotating conical piston pivoted therein, of a pivoted rotating and oscillating piston blade mounted in the piston, a movable inlet port for the actuating fluid, and a self-operating valve formed by a slot and passage in the shaft of the piston co-operating with a slot in the sleeve of the piston shaft, substantially as described. 120 125

22. In a rotary engine the combination with a rotating piston having a rotating and oscillating piston blade and a port in the piston 130

for introducing motive fluid behind said blade, of an inlet valve comprising two triangular ports one in the rotating shaft of the piston and the other in a sleeve surrounding said shaft with means for adjusting the intake of the same, substantially as described.

23. In a rotary engine the combination with a partispherical cylinder having a plane head set at an angle with the vertical, of a rotating piston provided with a retractile blade in contact with said piston head and coöperating therewith on one side of the center of the piston to form an inclosed space for the expansion of steam and means to admit steam and 15 cut off before the exhaust opens, substantially as described.

24. In a rotary engine in combination with a partispherical cylinder having an inclined head and a rotating piston with a conical face 20 in contact on one element with said head, and an exhaust port in the cylinder head near the said point of contact and an inlet port ar-

ranged to cut off so that the steam works expansively.

25. In a rotary engine the combination with a partispherical cylinder having a plane head inclined at an angle to the vertical, of a rotating piston and shaft said piston being slotted and provided with a retractile blade whose front edge coöperates with the inclined head 30 of the cylinder to give the said blade an oscillating motion through the said slot, while the rotary motion of the piston blade is imparted by the rotation of the shaft and proper inlet and outlet ports adapted to work the steam 35 expansively in the cylinder, substantially as described.

In testimony whereof I have hereunto set my hand in the presence of two subscribing witnesses.

WILLIAM A. SHEAHAN.
